UNITED STATES PATENT OFFICE.

FRANK A. BROWN, OF WILMETTE, ILLINOIS.

DESIGN FOR A JAR.

42,990.

Specification for Design.

Patented Sept. 10, 1912.

Application filed April 22, 1912. Serial No. 692,500. Term of patent 7 years.

To all whom it may concern:

Be it known that I, FRANK A. BROWN, a citizen of the United States, residing at Wilmette, in the county of Cook and State of Illinois, have invented a new, original, and ornamental Design for Jars, of which the following is a specification, reference being had to the accompanying drawing, forming part thereof.

The figure is an elevational view showing my new design for jars.

I claim:

The ornamental design for a jar as shown.

FRANK A. BROWN.

Witnesses:

WM. O. BELT,
M. A. KIDDIE.
